ELECTRIC SWITCH

Robert L. Gallup, Niles, Mich., assignor to McGill Manufacturing Company, Inc., Valparaiso, Ind., a corporation of Indiana

Filed Oct. 18, 1968, Ser. No. 14,055

Term of patent 14 years

Int. Cl. D13—03

U.S. Cl. D26—13

FIGURE 1 is a perspective view of an electrical switch showing my new design;

FIGURE 2 is a top plan view;

FIGURE 3 is a side elevation view;

FIGURE 4 is a front elevation view;

FIGURE 5 is a rear elevation view;

FIGURE 6 is a perspective view of a modified form of the switch shown in FIGURE 1.

I claim:

The ornamental design for an electric switch, as shown and described.
